UNITED STATES PATENT OFFICE

158,539

TELEVISION CABINET

Samuel E. Adler, Chicago, Ill.

Application May 5, 1949, Serial No. 2,452

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Television Cabinet, of which the following is a specification, reference being had to the accompanying drawing, forming part thereof.

Fig. 1 is a front perspective view of a television cabinet, showing my new design;

Fig. 2 is a side elevational view thereof; and

Fig. 3 is a top plan view.

The dominant features of my design reside in that portion shown in full lines on the drawing.

I claim:

The ornamental design for a television cabinet, as shown and described.

SAMUEL E. ADLER.
